MACHINE FOR PRESSING SOLES ON SHOES

Charles H. Pepin, Beverly, Mass., assignor to
United Shoe Machinery Corporation, Paterson,
N. J., a corporation of New Jersey

Application August 5, 1936, Serial No. 94,403
In Great Britain May 15, 1936

13 Claims. (Cl. 12—33)

This invention relates to cement sole attaching and sole laying machines which are provided with means for relatively locating a shoe and sole, and particularly to mechanism for controlling the locating means.

The invention is illustrated as embodied in a machine of the type disclosed in Letters Patent of the United States No. 2,047,185, granted July 14, 1936, upon the application of Ballard et al., which discloses a machine for cement-attaching soles to shoes comprising a plurality of pads which are brought successively to an operating station. Each pad is provided with shoe and sole locating gages which, after a sole is placed upon the pad, are allowed to engage the sole and become locked in operative position. A shoe is then placed upon the sole and is located relatively thereto by shoe gages carried by the sole gages. Pressure is then applied to the shoe to force it against the pad by fluid-operated pressure-applying mechanism which causes the shoe to be forced against the sole and depressed somewhat into the pad when the fluid pressure has been fully applied. Under these conditions the shoe may be brought quite forcibly against the locked gages before the shoe is fully depressed and during the dwell of the shoe under pressure the gages may occasionally indent or otherwise mar the shoe.

An object of this invention is to prevent such marring of the shoe.

Features of the invention consist in means, acting after sufficient pressure has been applied to the shoe to insure that the further pressure applied will not disturb the positions of the shoe and sole relatively to each other, to release the means for holding the gages in engagement with the shoe so that as further pressure is applied to the shoe the gages may be moved outwardly by the shoe and undesired pressure of the shoe against the gages avoided. Preferably release of the gages is effected by fluid pressure operated means which, as illustrated, is connected to the same source of fluid pressure as the means which applies pressure to the shoe. As illustrated, a plunger mounted in a chamber is exposed at one end to fluid pressure acting to move the plunger in one direction, and movement of the plunger in that direction is opposed by spring means so that only after the fluid pressure back of the plunger has been built up to a predetermined pressure sufficient to overcome the spring means does substantial movement of the plunger occur. Movement of the plunger thereafter by the increased

pressure acts to release the lock which holds the gages against the shoe.

These and other aspects and features of the invention will now be described with reference to the accompanying drawings and will be pointed out in the appended claims.

In the drawings,

Fig. 1 is a front elevation of part of the machine embodying the present invention;

Fig. 1a is a detail of the pump for producing sole-attaching pressure;

Fig. 2 is a plan view of the forepart of one of the pad boxes with which the machine is equipped showing the gage mechanism;

Fig. 3 is a sectional view of the part shown in Fig. 2;

Fig. 4 is a side elevation, partly in section, showing one of the pad boxes and the mechanism for applying pressure to the shoe;

Fig. 5 is a front view of the mechanism for controlling the operation of the gages including fluid-operated means for releasing the gages;

Fig. 6 is a detail, partly in section, of the fluid-operated means for releasing the gages;

Fig. 7 is a side elevation of part of the mechanism shown in Fig. 5; and

Fig. 8 is a plan view of the mechanism shown in Fig. 7.

In the drawings my novel mechanism for releasing the gages is disclosed as embodied in a machine of the type fully described in the above-mentioned patent. The drawings show those parts of the machine with which my invention is directly concerned and for an explanation of parts of the machine not herein fully described reference may be had to the above-mentioned patent.

In the drawings, the numeral 10 (Fig. 1) indicates part of a turret arranged on a column 12 for rotation about a vertical axis, the turret carrying a plurality of pad boxes, 14, 14, containing pads which are presented in turn at an operating station, at which station the mechanism shown in Fig. 1 is located. One of the pad boxes 14 is shown more fully in Fig. 4. The pad box contains a yielding pad 16 and upon this pad a sole A is placed preparatory to its being attached to a shoe. For holding the sole and for locating a shoe relatively to it, mechanism shown in Fig. 2 is provided. After placing the shoe on the pad, the operator, by depressing the treadle 18, causes gages 20 to approach the sole at four points located approximately at opposite ends of the ball line and opposite ends of the tip line. Each of the sole gages 20 is carried by a separate arm, 55

arms 22, 24 carrying the ball line gages and arms 26, 28 carrying the tip line gages. The arm 22 is pivoted by a horizontal pin 30 to a member 32 which in turn is pivoted on a fixed substantially vertical pin 34 on a frame 35 secured to the pad box 14. The gage arm 28 is pivoted by a horizontal pin 36 to a member 38 also pivoted on the pin 34. Similarly, the gage arm 24 is pivoted by a pin 40 to a member 42 which is pivoted on a fixed pin 44 similar to the pin 34, and the arm 26 is pivoted by a pin 46 to a member 48 also mounted on the pin 44. Each arm is swung about its pivot in a direction to move its gage toward the shoe by a separate spring, the arm 22 being so moved about its pivot 34 by a spring 50 and the arm 28 being moved by a spring 52 about the same pivot. Springs 54 and 56 act, respectively, on the arms 24 and 26 to swing them toward the shoe about the pivot 44. The gages 20 rest directly upon the pad 16, and the gage arms 22, 24, 26 and 28 can swing about their respective pivots 30, 40, 46, 36 so that the gages 20 may move heightwise of the shoe if necessary, for instance, when the surface of the pad is distorted. The gage arms 22, 24, 26 and 28 are moved about their pivots 34, 44 to move the gages 20 away from the sole against the springs 50, 52, 54, and 56 by movement of a rocker 58 (Fig. 3) mounted on a shaft 60. The rocker 58 has four upward projections 62, one for each of the gage arms, these projections engaging rolls 64 mounted one on each of the gage arms in such relation to their pivots 34, 44 that pressure of the projections upon the rolls due to counterclockwise movement of the rocker 58 will move all the gages away from the sole simultaneously.

After the gages 20 have been allowed to engage the edge of the sole they are locked in sole-engaging position. For this purpose portions of the members 32, 38, 42, and 48 which carry the gage arms are arranged to overlap each other and are provided with slots through which a locking bolt 66 (Fig. 3) passes. The bolt 66 is provided at its upper end with a washer 68 and nut 70 and near its lower end has a notch which is engaged by a tooth 72 formed on a lever 74 pivoted at 76 and urged by a spring 78 in a direction to clamp the members 32, 38, 42 and 48 together and against a part 80 of the frame 35 which is secured to the pad box. The lever 74 has a roll 82 mounted thereon between its fulcrum 76 and the spring 78 which is engaged by a cam surface on the rocker 58 early in its counterclockwise movement to lift the lever 74 against the spring 78 and release the locking bolt 66, further movement of the rocker 58 moving the gage arms away from the sole. The rocker 58 (Fig. 3) is connected by a link 84 (Fig. 2) to an upright arm 86 of an angle lever (Fig. 5) pivoted at 88 to the turret, the angle lever having a horizontal arm 90 to be referred to later. The right-hand end of the link 84 carries a pin 92 one end portion of which lies in a slot 94 formed in a member 96 fixed to the frame 35 and the other end of which carries a roll 98 (Fig. 2) which engages a slot formed in the upper portion of the arm 86. It will be seen that when the horizontal arm 90 of the bell crank lever is raised the link 84 will be pushed and the rocker 58 swung counterclockwise about its pivot 60 to unlock and open the gages, as above described. A spring 100 (Fig. 5) connected between the arm 86 and a pin 102 on the turret 10 tends to swing the arm 86 in a clockwise direction and hold a stop screw 104 against a portion of the turret.

It is to be understood that each of the pad

boxes 14 with which the machine is equipped is provided with a duplicate of the above-described mechanism. When one of the pad boxes approaches the operating station, a roll 106 on the arm 90 engages a stationary cam 108 and is lifted to open the gages, and when the roll 106 stops at the operating station it rests on a ledge 110 (Figs. 7 and 8) forming a continuation of the top surface of the cam 108, the ledge 110 being carried by a lever 112 pivoted to the cam member 108 at 114. The lever 112 may be depressed by movement of the treadle 18 which pulls downwardly on a rod 116 against a spring 118, the rod 116 being connected at 120 to the lever 112. A latch 122 (Fig. 5) is provided for locking the lever 112 in 15 depressed position, which latch may be manually released by moving a handle 124 toward the right against a spring 126 and is automatically released when the turret rotates by engagement of a roll 128 on the shaft 88 with a projection 130 on the 20 latch 122. Of course, as the treadle 18 moves the ledge 110 downwardly away from the roll 106 the spring 100 reacts to pull on the link 84 and move the rocking member 58 clockwise, thus permitting all of the gage-closing springs 50, 52, 54, and 56 25 to close the gages against the sole, and finally the spring 78 is allowed to act to lock the gages in position.

Each gage 20 carries a shoe gage 132, each of these being adjustable by means of a handle 134 30 relatively to the corresponding sole gage 20 as explained in the above-mentioned patent.

The operator, after laying the sole A having activated cement upon its marginal portion upon the pad 16, will operate the treadle 18 to permit 35 the gages 20 to come in contact with the sole and become locked in position by the mechanism described, and will place a shoe B having cement upon the overlasted portion of its upper upon the sole A with its upper in contact with the four 40 shoe gages 132, the forepart of the shoe being thus located relatively to the sole. Pressure is now applied to the shoe to force it down upon the sole and hold it in that position until the cement has set. For this purpose each pad box 45 14 is provided with pressure-applying mechanism (Fig. 4) which comprises a cylinder 136 in which is a piston 138 carrying at its upper end a lever 140 each end of which is disposed under a lever 142 pivoted at 144. One of the levers 142 carries a block 146 to engage the top of a last and the other lever 142 carries a toe rest 148 to engage the toe portion of the shoe. It will be seen that by upward movement of the piston 138 due to the introduction of fluid under pressure 55 through a pipe 150 the levers 142 will be operated in a direction to force the shoe down upon the pad 16, and that, if the gages 20, 132 remain locked against the shoe, the shoe as it is depressed into the pad may be forced against the gages, 60 or some of them, in such a manner as to mar or otherwise injure the shoe.

By my invention means is provided to release the gages and prevent injury to the shoe, this means as illustrated being operated by the fluid pressure which forces the shoe into engagement with the pad. This means comprises mechanism which is shown in Figs. 6, 7, and 8. A member 152 is bolted at 153 to a bracket 155 secured at 157 to a stationary post 159. At its upper end 70 the member 152 is provided with a cylindrical bore to receive a plunger 154 which has a running fit in the bore. One end of the bore is threaded to receive a supply pipe 156 and the other end of the bore is enlarged and threaded to 75

receive a plug 158 through which a pin 160 is freely movable. A pipe 162 is connected with the bore so that any fluid, such as oil, which passes the plunger 154 may be drained away and be carried to the tank which supplies a pump 163 for producing the pressure. This pump 163 which may be a continuously driven gear pump is connected between a pipe 164 (Fig. 1a) which supplies oil to the pump and a pipe 166 which receives oil from the pump. The pipes 164, 166 are connected by a pipe 168 in which is a valve 170 (Fig. 7) which, when open, allows the oil to be freely circulated by the pump and when closed causes pressure to be produced in the pipe 166 for operating the piston 138 and the plunger 154, the pipe 156 which supplies the plunger being connected to the pressure pipe 166 at 172 (Fig. 1). The pipe 166 is also connected through a three position valve 173 to the pipe 150 which supplies pressure to the piston 138. The valve 170 is closed by operation of a treadle 174 depression of which pulls downwardly on a rod 176 against a spring 178, the rod 176 having a collar 180 (Fig. 7) between which and a washer 182 is a spring 184. The washer 182 rests on the forked end of a lever 186 pivoted at 188 and connected at its rear end by a link 190 to a lever 192 upward movement of which closes the valve 170. The valve 170 is maintained in open position by a spring 194. As shown in Fig. 7, the member 152 in which the plunger 154 is located is provided with a bifurcated upward extension 196 having ears to which a member 198 is pivoted at 200. The member 198 carries a pin 202 connected by a spring 204 to the extension 196, which spring tends to turn the member 198 in a counterclockwise direction and to hold a screw 206 threaded through its lower portion in contact with the pin 160 on which the plunger 154 acts. The member 198 carries a projection 208 which, when one of the pad boxes is located at the operating station, lies immediately under a lever 210 which is pivoted on the shaft 88 and is fastened by a bolt 212 to the arm 90 so that it forms substantially a part of that arm, upward movement of which causes the gages to be released. It will now be seen that when the treadle 174 is depressed to close the valve 173 pressure will be supplied to the piston 138 which is at the operating station and when, due to resistance of the shoe, the pressure has been built up sufficiently in the pipe 156, the tension of the spring 204 will be overcome and the plunger 154 will be operated, causing the member 198 to be turned about its pivot 200 and the projection 208 forced against the lever 210, thereby lifting the lever and the arm 90 sufficiently to unlock the gages and avoid injurious pressure of the shoe against them as the piston 138 is further operated to apply full pressure to the shoe. It will also be seen that it is necessary to provide only one of the plungers 154 and its attendant mechanism since this mechanism operates in turn on each of the gage mechanisms when it is presented at the operating station. For the spring 204 a spring of such strength will be selected that the pressure behind the plunger 154 can overcome the tension of the spring to operate the projection 208 sufficiently to unlock the gages only after a predetermined pressure, less than the maximum, has been applied to the shoe, the gages preferably being released after only sufficient pressure has been applied to insure that there will be no relative shifting of the shoe and sole during the further application of pressure to the shoe.

To the treadle 174 is connected, as shown, the usual mechanism for moving the three-position valve 173 to inlet position when the treadle is depressed to apply pressure to the pad at the operating station and to the same treadle is connected the usual mechanism for moving the three-position valve of the pad next to come to the operating station to exhaust position as fully explained in the patent hereinbefore mentioned. This mechanism forms no part of the present invention and accordingly a detailed description thereof is omitted.

In the following claims the phrase "cement sole attaching machines" should be taken as illustrative and as of a scope to include, for example, sole laying machines which are used for the temporary attachment of soles, preliminarily to the stitching of the soles to the shoes.

Having thus described the invention, what I claim as new and desire to secure by Letters Patent of the United States is:

1. A machine for applying pressure to shoe bottoms having, in combination, a pad arranged to apply pressure to a sole and shoe, means for relatively positioning the sole and shoe on the pad, means for locking the positioning means in operative position, and fluid-pressure-controlled means for releasing said locking means.

2. A machine for applying pressure to shoe bottoms having, in combination, a pad arranged to apply pressure to a sole and shoe, means for relatively positioning the sole and shoe on the pad, means for locking the positioning means in operative engagement with the sole and shoe after they have positioned them relatively to each other on the pad, and fluid-pressure-controlled means for releasing said locking means.

3. In a cement sole attaching machine, the combination of a plurality of pads arranged to be presented in turn at an operating station, gages associated with the pad at the operating station for relatively locating a shoe and sole placed upon the pad, means for locking said gages in operative position, fluid-pressure-operated means for moving the shoe and pad relatively to each other to press the sole upon the shoe, and fluid-pressure means operating after a predetermined pressure has been applied to the shoe for releasing the gages.

4. In a cement sole attaching machine, the combination of a plurality of pads arranged to be presented in turn at an operating station, gages associated with the pad at the operating station for relatively locating a shoe and sole placed upon the pad, means for locking said gages in operative position, fluid-pressure-operated means for moving the shoe and pad relatively to each other to press the sole upon the shoe, and fluid-pressure means operating after a predetermined pressure has been applied to the shoe for releasing the gages.

5. In a machine for cement-attaching soles to shoes, a pad box, a pad mounted in the box, shoe and sole locating means carried by the box and movable to engage a shoe and sole located on the pad, means for locking the shoe and sole locating means in operative position, means for relatively moving the pad and shoe to press the shoe and sole together, and means operated by the applied pressure and before maximum pressure is reached to unlock the shoe and sole locating means.

6. In a machine for cement-attaching soles to shoes, a pad box, a pad mounted in the box, shoe and sole locating means carried by the box and

movable to engage a shoe and sole located on the pad, means for locking the shoe and sole locating means in operative position, means for moving the shoe to press it upon the pad, and 5 means for automatically unlocking the shoe and sole locating means after a part only of said pressure has been applied.

7. In a machine for cement attaching soles to shoes, a pad box, shoe and sole locating gages 10 carried by the pad box and movable to engage a shoe and sole located on the pad, a lock for holding the gages in operative position, and means for releasing the lock, said means acting automatically only after sufficient pressure has 15 been applied to prevent relative slipping of the shoe and sole.

8. In a cement sole attaching machine, the combination of a plurality of pads arranged to be presented in turn at an operating station, 20 means associated with each pad for relatively locating a shoe and sole placed upon the pad, means for locking said locating means in operative position, means for applying pressure to the shoe to force it against the pad, and means 25 operated by the pressure-applying means after a predetermined pressure has been applied to the shoe for releasing the locking means.

9. In a cement sole attaching machine, the combination of a plurality of pad boxes arranged 30 to be presented in turn at an operating station, pads in the boxes, means associated with each pad for relatively locating a shoe and sole placed upon the pad, means on each pad box for locking said locating means in operative position, means 35 for applying pressure to the shoe to force it against the pad, and a single means located at the operating station and operating automatically only after a predetermined pressure has been applied to the shoe for releasing each locking 40 means in turn.

10. In a cement sole attaching machine, the combination of a plurality of pad boxes arranged to be presented in turn at an operating station, pads in the boxes, means carried by each of the 45 pad boxes for relatively locating a shoe and sole placed upon the pad, means for locking said lo-

cating means in operative position, means for applying pressure to the shoe to force it against the pad, and means located only at the operating station and operating automatically after a predetermined pressure has been applied to the 5 shoe for releasing the locking means.

11. In a machine for cement-attaching soles to shoes, a pad box, a pad mounted in the box, shoe and sole locating means carried by the box and movable to engage a shoe and sole located 10 on the pad, means for locking the shoe and sole locating means in operative position, fluid operated means for relatively moving the pad and shoe to press the shoe and sole together, and fluid operated means acting during the application 15 of pressure to unlock the shoe and sole locating means.

12. In a cement sole attaching machine, the combination of a plurality of pad boxes arranged to be presented in turn at an operating station, 20 pads in the boxes, means associated with each pad for relatively locating a shoe and sole placed upon the pad, means on each pad box for locking said locating means in operative position, a source of fluid pressure, a piston and cylinder for 25 each pad operated from said source for applying pressure to the shoe to force it against the pad, and a single fluid operated plunger located at the operating station and operated from said source after a predetermined pressure has been applied to the shoe for releasing each locking 30 means in turn.

13. In a cement sole attaching machine, the combination of a plurality of pad boxes arranged to be presented in turn at an operating station, 35 pads in the boxes, gages carried by the boxes for relatively locating a shoe and sole placed upon the pad, means for locking said gages in operative position, a piston and cylinder associated with each pad box for applying pressure to the 40 shoe to force it against the pad, and a cylinder and plunger located only at the operating station and operating after a predetermined pressure has been applied to the piston to release 45 the locking means.

CHARLES H. PEPIN.
